KNITTED FABRIC AND METHOD OF AND APPARATUS FOR MAKING THE SAME

William J. Wesseler, East Cleveland, Ohio

Application August 31, 1931, Serial No. 560,398

19 Claims. (Cl. 66—1)

This invention relates to knitted fabric and to the method and apparatus for producing the same. More particularly, the invention comprises a fabric of the general type shown in my Patent 5 No. 1,738,486, and embodying additional features to that disclosed therein, such fabric being formed by a knitting operation wherein the stitches or loops making up the same may be drawn to any desired size and may be so tightly seated upon adjacent stitches or loops as to present what may be termed a "needle-tight" fabric. Such fabric may be used as a plain or finished fabric.

The invention also has in view the provision of apparatus for producing the various types of fabric 15 described, such apparatus embodying means for producing tightly pulled loops or loops drawn to predetermined size, with or without interlocked additional or auxiliary threads. Apparatus is also provided to produce purl fabric in a novel manner 20 at high speed and with or without tightly drawn loops and in plain form or with additional pile or other yarns interlocked therewith.

Other and further features of the invention will appear in the course of the following description. 25 The annexed drawings and the following description set forth in detail certain fabrics and the means and mode of carrying out the invention, such disclosed means and mode illustrating, however, but several of the different ways in 30 which the principle of the invention may be used and the fabrics produced.

Fig. 1 is a side elevation showing one form of apparatus embodying the principles of the invention;

35 Fig. 2 is a top plan view of the apparatus shown in Fig. 1;

Fig. 3 is an enlarged view of a loop forming ring, shown for convenience with four yarns in place of a large number such as are shown in Figs. 1 and 2;

40 Figs. 4, 5 and 6 are fragmentary perspective views showing the operation of forming a loop;

Fig. 7 is a view showing a portion of the loop forming ring provided with another type of loop forming member;

45 Fig. 8 is a diagrammatic view showing the path of movement of the modified type of loop forming element;

Figs. 9 and 10 are fragmentary perspective views 50 showing the loop-forming operations of the modified type of loop forming member;

Fig. 11 is a fragmentary perspective view showing a portion of plain fabric formed on my improved apparatus, the loops being shown enlarged 55 and of loose structure to illustrate the loop construction and their relation to the yarn feeder tubes and loop forming elements;

Fig. 12 is a view similar to Fig. 11 showing the incorporation of filling material with the plain 60 fabric shown in Fig. 11;

Fig. 13 is a perspective view showing a presser plate and clamping plate in non-clamping position with four yarns shown in place of a large number running freely;

Fig. 14 is a view similar to Fig. 13 showing the 65 manner of supplying filler yarns to the yarn feeds; and

Fig. 15 is a diagrammatic view showing the loop forming operation with filler yarns on one side of the fabric. 70

As has been indicated, the apparatus illustrated is adapted to carry out the principles of my invention as set forth in my Patent No. 1,738,486. Such apparatus, in each instance, forms a loop on each needle or other knitting instrumentality 75 from yarns of one series and thereafter forms a second loop on each needle or other knitting instrumentality from a separate series of yarns simultaneously casting off the loops formed from the first series of yarns and thereafter repeats 80 the process from the beginning. For these operations the apparatus I have shown is to be understood to be merely illustrative and that the invention may be embodied in a wide variety of machines of substantially all known types, particularly those wherein united needle operations are carried on, whether in the form of straight machines or circular machines. 85

The type of apparatus illustrated is adapted for 90 the production of purl type knitted fabric and for filler fabric or pile fabric having a purl knitting backing with which the filler yarns are interlocked.

As stated, this apparatus may produce plain 95 fabric as well as filler fabric or pile fabric, and the plain fabric may be of the purl knitted type or may incorporate various features of other conventional types of fabric. The purl type fabric is substantially of what is known as "links and links" and instead of being formed by means of double ended knitting needles is preferably formed upon a special type of loop former. By whatever method formed my method permits the drawing of the loops to any desired size by applying 100 tension to the individual yarns of the cast off loops. In the form of construction shown in Figure 1 the loop-forming instrumentalities are rotatable, while the yarn feeders are substantially 105 stationary and the tensioning devices employed have merely reciprocatory movement toward and away from the knitting throat.

The invention is applicable to machines which "shog" back and forth, but shogging results in the formation of a relatively thick fabric and the 110 preferred type of machine is that which will knit continuously in one direction.

The machine illustrated in Figs. 1 and 2 particularly, is designed to make links and links or purl fabric in either plain or filler type of product. 120

As clearly shown in the drawings, it comprises a base member 1 in the form of an elongated support upon which are mounted in spaced relation to the base a pair of aligned tubular members 2, 3, 5 supported at their outer ends and having their free ends extending toward the center of the machine to a point where they are spaced from each other a distance slightly more than necessary to permit the newly formed loops to move into the 10 interior of one of such tubes. This space 4 has been designated the "knitting throat". For heavier fabric the interior diameter of the tubes must be increased as well as the space between the ends thereof.

15 The tubular members, as indicated, are supported at their outer ends, respectively, and in order to have free adjustment of such tubes vertically, the supports employed comprise standards 5 having upper portions telescopically engaged 20 with their bases and held at any desired elevation by set screws. The upper portion is formed with spaced arms having set screws extending inwardly from either side which serve to grip the tubular member. The set screws on the arms permit angular 25 horizontal adjustment to a slight extent of the tubular members. The finished fabric 6 is fed through one of the tubes and may be received over a roller provided with a weight or over a reel 7 as shown, having a suitable ratchet mechanism 8 to prevent the reversal of the same, and which 30 will permit the application of suitable tension to the finished work, if desired. At the inner end of each of the tubes a series of yarn feeds 9, 10, respectively, are provided, said yarn feeds preferably being formed of tubes of small diameter 35 having their outer ends firmly secured to the tubular support and having their inner ends free. The free ends of the yarn feeds are suitably formed to assist in the loop drawing operation with the 40 loop-forming members presently to be described. Thus, the yarn feeding tubes extend in the direction of the supporting tube adjacent its outer surface and then extend at a slight angle toward one side and may extend slightly downwardly, so as to provide on the under side thereof a space for 45 the engagement of the new yarn by the loop-forming member.

The number of yarn feeds, and loop forming members, of course, corresponds to the size of fabric which it is desired to manufacture and they 50 may be increased to a very great extent, although the weight of the finished fabric and the power necessary to move the loop-forming ring are factors which enter into the question of the design of the larger types of machines.

55 A machine for utilizing a large number of yarns is illustrated in Figure 1, whereas in Figure 3 and in the diagrammatic views an apparatus using merely four yarns on each side is shown in order that the operations of forming the loops may be more readily understood, but it is not intended in any way to limit the apparatus to one wherein a small number of yarns are used, as the machine is adapted to operate in large units for forming fabrics of standard commercial widths or even in excess of commercial widths now recognized as practical.

70 The take-up reel is shown in line with one of the tubular supports 3. On the opposite end of the apparatus the power supplying means is positioned, as will be presently described.

75 The yarn feeds, as stated, are held in fixed position upon the tubular members which are firmly supported centrally of the base in spaced relation thereto. The yarns 12 extend toward

the yarn feeds from a source of yarn supply in the form of spools 13 located adjacent the outer ends of the respective tubes, there preferably being one spool for each yarn, together with a take-up support 14 which acts frictionally against the spool until a high degree of tension is reached. This prevents undue slack in the yarn as the reciprocating parts of the machine operate. The yarns extend from the reels through guide eyes or a guide plate 20, and thence through apertures 16 in a presser plate 17, there being an individual aperture for each yarn, and extend from said presser plate through apertures 18 in a clamping plate 19, which likewise has individual apertures for each yarn, slightly offset from direct alignment with the apertures in the corresponding presser plate, as shown in Fig. 13. A presser plate and clamping plate is provided on each end of the apparatus, said plates being preferably slidably mounted by having bearings 21 adjacent 90 their side edges engaged over bars 22 which form trackways or slideways for said plates. In the form of construction shown, one longitudinal bar is provided on each side of the apparatus, said bar being supported at the ends of telescopic 100 standards 23, which are adjustable horizontally with reference to the base. The upper sections of the standards are received in sockets which are provided at the ends of slotted bracket arms 24, which are held to the base by means of bolts 25. 105 Thus, the bars or trackways may be moved outwardly from the central line of the machine, or the brackets may be swung at an angle with reference to the machine in order to change the position of the trackways, and such adjustment 110 may be firmly maintained by securing the bolts firmly to the base of the device. By means of set screws 26 on the socket portions of the bracket arms the standards may be raised and lowered so as to bring the trackways at any desired elevation with reference to the tubular supports for 115 the yarn feeds.

Intermediate the clamping plates the loop forming plate 27 is positioned, said plate likewise being supported on the trackways by means of 120 suitable bearing members, such as lubricated sleeves engaged over said bars or any other desirable means of support. The loop forming plate is formed centrally with a bearing 28 to receive the loop forming ring 29 which, in the 125 form of construction shown, is a flanged member having a large central opening into which project the individual loop forming members 31 of the apparatus.

The loop forming members may take various 130 shapes, being dependent in some measure upon the particular shape of the yarn feeding device which cooperates therewith. In fact, any suitable instrumentalities whether needles, bars, or other devices, may be used in forming the loops 135 so long as they hold a loop on the instrument and engage a yarn in such relation to the retained loop as to draw the yarn through such loop in the course of the movement of the loop-forming member or the movement of either the 140 loop-forming member and yarn feed, relatively to each other.

As is clearly shown in Figures 4, 5 and 6, the loop-forming members 31 comprise metal plates being preferably supported at their top or side 145 edges on the loop-forming ring and having their free edges shaped in the form of hook-shaped terminals 33 projecting toward a point adjacent the center of the aperture through the ring. The edge of the hook member is adapted to ride be- 150

neath the yarn feeding tube and terminates in a point 34 which is adapted to engage the yarn within the yarn feeding tube 9 and draw it through the loop 36 carried on such loop-forming member which has been spread through the co-action of the yarn feeding tube and the loop-forming member. This cooperation of said members is brought about through the reciprocation of the loop-forming ring back and forth across the knitting throat and the movement of the ring around its axis at certain specified times by a worm and gear in larger machines, or by pins 37 and cam plates 38, 39, in the form shown. A yarn engaging hook will first be moved longitudinally of the apparatus in a substantially straight line to draw a loop, and will then by contact of the pins with the plates be rotated a distance sufficient to pass such loop-forming member behind the inclined portion of the opposite yarn feed 10 and advance beyond the same radially a distance sufficient to permit the hook on said particular loop-forming member to engage beneath the opposite yarn feed in slightly advanced relation to the previous yarn feed. The loop-forming ring then enters on its movement in the opposite direction in a straight line, the tubular yarn feeds also functioning as guide members. A notched spring finger 40 frictionally positions the pins.

It will be noted from the showing in Figures 4 to 6 that as the loop-forming member passes behind the inclined yarn feed, it spreads the loop over the inclined portion of the yarn feed and as it advances toward the free end of the yarn feed it holds the retained loop spread apart sufficiently to permit the outer portion of the bight of the loop to ride off the free end of the yarn feed, while the other portion of the bight of said loop will still be engaged over said tube. The point of the loop forming member at this stage of the operation will ride past the end of the tube and will receive upon its hook-shaped advancing edge the new yarn from within the yarn feeding tube. The straight edge 35 of the yarn feeding member will prevent the tube engaging portion of the loop from disturbing the position of the yarn within the hook on the advancing edge of the member, and the knock over portion of the tubular support for the yarn feeds will cause the bight of the loop to remain open and be disposed below the point of the loop-forming member which is in the act of engaging the new yarn and putting the same through such open bight.

As the loop-forming member 31 advances to the position shown in Figure 6 the new loop 12a is being drawn forward toward the opposite supporting tube 10 across the knitting throat and the previously retained loop 12b is being cast off from the loop-forming member 31, the edge of the opposite tube serving as a knock over member to prevent said loop interfering with the new loop. As this operation proceeds certain other operations are being initiated. Thus, the clamping plate in the direction of motion is being pressed against the presser plate at that end of the slideway. The presser plate 17 has positioned rearwardly of the same a pair of coiled springs 41 engaged over the slideway bars, and these springs are placed under compression as the clamping plate 19 bears against the opposite surface of the presser plate. When the clamping and presser plates are thus engaged the individual yarns on that side of the apparatus are firmly held against free running feeding movement,

and as the clamping plate and presser plate are moved together with the yarns all tightly clamped between said plates, the yarns will be drawn upon individually so that they will run reversely through the yarn feeding tubes, and the cast off loops will be drawn to small dimensions, depending on the distance of movement of the clamping and presser plates. If such distance of movement is sufficiently great, extremely high tension will be applied to the individual yarns and the loops cast off at the knitting throat will be drawn to a tight seat within the space between said tubes. Thus with each endwise movement of the plates a complete course of loops will be finished around the entire circumference of the fabric margin. The tubular knitted product will pass through the supporting tube shown on the right-hand side of Figure 1 and will be taken up on the take-up roller 7 at the end of the base member. By cutting the finished fabric along a spiral line the fabric may be supplied as flat fabric with loops extending straight across instead of running on the bias.

As stated, a similar presser plate and clamping plate is provided at the opposite end of the apparatus and as the direction of movement of the plates is reversed they will spread the newly formed loops and pull a new yarn through the open bight thereof. The operation of forming a loop is thus repeated continuously in substantially the same manner as that first described, and a second course of finished loops is firmly seated on the fabric margin as the loop-forming ring and the clamping and presser plates are moved toward the opposite end of the machine. Thus, with each movement of the apparatus in one direction or the other, a complete circumferential series of loops is formed.

In place of the loop-forming members shown in Figs. 3 to 6, inclusive, members of the type illustrated in Figs. 7 to 10, inclusive, may be used. With loop-forming members of the type shown in Figs. 7 to 10, inclusive, plates 30 provided with triangular projections 32 on each edge are adapted to form substantially vertically positioned loops of the yarn received through the yarn feeding tubes. The loops, as will be noted from the drawings, are spread vertically a sufficient distance to permit the point opposite the one holding such loop to project through the open loop and pick a new yarn after the loop-forming member has been moved diagonally to a position rearwardly of the new yarn. If desired, the loop-forming member may be pivoted so as to rock the point for engaging the new yarn outwardly so as to more readily engage the same. Such movement may be caused by the pressure of the old yarn on the member against a fin projecting from the yarn engaging point.

Whether such loop-forming elements are made as rigid elements or as pivoted members just described, the action of the device is substantially the same.

This form of loop-forming element is adapted to draw a smaller loop than would be required with certain other types of loop-forming elements particularly where a large number of yarns are used, and the yarn feeds are very closely spaced together. In such case, the angular movement of the yarn-engaging member will be very slight, and the speed of motion of the loop-forming ring might be at a very high rate.

Because the degree of movement of the loop-forming ring being very short longitudinally of the machine, the loops themselves will be of very

small size and the degree of tensioning movement of the clamping and presser plates will be proportionately reduced. However, as heretofore stated, through the use of springs to shift the 5 loop-forming ring longitudinally in each direction, and stops to limit the movement of the loop-forming ring to a short range of motion, the 10 yarn tensioning movements may be carried on to any desired degree after the loop-forming ring 10 has reached its limit of motion in each of the respective directions of movement. Such mechanism has been indicated in Figs. 1 and 2.

The method of forming filled fabric or pile fabric with this mechanism may be variously carried out, but with the mechanism illustrated may be accomplished by placing in each of the feeder tubes at one side of the apparatus both a tensioning yarn 12 and a filler yarn 12c. The tensioning 15 yarns extend through the offset apertures 16, 20 18, in the clamping and presser plates, and the filler yarns extend through aligned apertures 12d, 12e, in said plates, or have independent paths around the clamping and presser plates so that no clamping and tensioning action is applied to 25 the filler yarns which accordingly are knitted in without tension. Thus, if mohair pile fabric is to be manufactured, a mohair yarn 42 or even mohair "slubbing" may be fed through one series of tubes paralleling one of the series of tubes 30 for the backing yarns or through the same tubes 9 as the single series of backing yarns and the mohair will be tightly interlocked with the backing fabric through the pull of the tensioning device upon the individual yarns. If it is desired 35 to have a double face pile fabric the filling material or, in the example cited, the mohair, may be supplied through the yarn feeder tubes of both series and the tension merely applied to the backing 40 yarns of each of said series as they are alternately knitted and cast off.

The method of producing the fabric has been outlined, but the means for shifting the plate carrying the loop-forming ring and the clamping and presser plates has not yet been indicated.

45 This mechanism will now be described.

At the end of the base plate opposite the position on the take-up mechanism the operating mechanism for the device is shown. This comprises an electric motor 43 carrying a pinion 44 meshing with a gear wheel 45 operating a crank 50 shaft 46, the crank of which is connected by a link 47 with pivots 48 to a rocking frame 49. The rocking frame has a pivot 50 at its lower portion on each side of the base board and carries at 55 each of its sides edges outwardly projecting pivot pins 51 interengaged with slideways 52 at the margins of said frame and adjustable toward or away from the pivots 50 of said frame, preferably by means of vertical positioning screws 53. 60 Upon each of said pivot pins links 54 are engaged, the other ends of which are passed through wide apertures 55 in the adjacent presser plate and are engaged upon pivot pins 56 secured to studs 57 mounted adjacent the central portion of the clamping plate at that end of the apparatus. 65 This clamping plate is connected with the clamping plate on the opposite side of the apparatus by adjustable side bars 58. The loop-forming plate 70 27 is positioned between said clamping plates and is operated by them. Any desired degree of lost motion between the clamping plates and loop-forming plate may be provided for.

75 Through the mechanism described the clamping plate is moved back and forth as the crank shaft rotates, and the speed of the apparatus

may be controlled in accordance with the character of the fabric being formed. With smooth surfaced, fast running yarns, such as silk threads and the like, a higher speed of operation may be carried on than where the yarns have surfaces 80 involving a degree of friction. Likewise, where the yarns are of uncertain strength the speed of operation of the machine must be reduced proportionately so as not to impose too great a strain 85 on the material with the change of direction of motion of the apparatus.

By shifting the pivot pins 51 at the margin of the frame downwardly or upwardly, the stroke of the apparatus can be greatly varied and thus the loops may be drawn to a degree of tension very 90 nicely adjusted to the requirements of the material worked with. If desired, the power may be applied to the clamping plate through buffer spring connections 59 comprising fairly heavy 95 springs on each side of the bolt which will be brought into action only when an excess of power is applied to the apparatus through the catching of the yarns or some other incident of operation which interferes with the free running of the apparatus. The tension on these springs may be 100 varied by turning the nut provided on the end of the relatively long bolt.

If a shorter range of action is desired for the loop-forming plate, similar buffer springs may be used, suitable stops being provided to limit the 105 travel of the loop-forming plate. The tensioning action can thus be continued after the loop-forming plate comes to rest.

As has been stated, and as will appear from Figures 1 and 2 of the drawings, the first described clamping plate is connected with the other clamping plate by means of adjustable side bars 58 so that the degree of space between the same may be changed as desired. Thus, with the two clamping plates 19 rigidly held together, the 115 operation of the motor will slide the clamping plates and produce gripping and tensioning action alternately at opposite ends of the apparatus.

The plate carrying the loop-forming ring, as shown in Figures 1 and 2, is disposed intermediate the two clamping plates, the sleeves 60 of the ring plate sliding on the respective side bars 22 and being engaged at different stages of the motion of the clamping plates 19 by the sleeves 21 supporting said respective clamping plates. 120 Thus, as the clamping plates are moved back and forth the adjacent ends of the sleeves or interposed washers will be brought into operative contact with portions of the ring supporting plate and will shift said last-named plate back and 125 forth during a portion of the range of motion of the clamping plates. The degree of motion to be imparted to the loop-forming plate depends upon the depth of stroke necessary to form satisfactory loops and the excess amount of motion over this minimum that is necessary for the tightening of the loops cast off. The tightening operation on the cast off loops may commence slightly in advance of the loop-forming movement to take 130 excess slack out of the yarns or it may continue 135 after the loop-forming movement is completed.

The degree of motion of the tensioning plates at either end of the apparatus likewise may not be uniform in extent for the reason that where filler fabric is fed through the yarn feeding tubes, 140 the loops engaging about said filler fabric cannot be drawn to as close a set as the loops on the opposite side which are free of filler fabric. In order to provide for this difference in tensioning movement the position of the presser plates with 145

reference to their respective clamping plates is varied and the pressed plate for tensioning the side of the apparatus having the filler fabric will be held to a shorter range of motion toward the 5 knitting throat than will be permitted the presser plate at the opposite end of the apparatus.

The means for limiting the movement of the presser plates toward the center of the apparatus comprises limiting stops in the form of rods 61 10 connected with pivot members 62 on the respective presser plates on their outer end faces and screw-threaded at their free ends to receive a stop nut 63 and a locking nut 64 therefor. Said bars engage through eyes 65 at the sides of the standards and through engagement therewith stop the movement of the presser plates toward the knitting throat toward which they are normally moved by the coiled springs on the respective side bars.

20 The strength of the springs may be adjusted by sliding the collars 66 engaged over the respective slide bars and forming abutments for said springs toward or away from the knitting throat and locking said collars in any desired position by means of the set screws 67 therein.

If desired, a mandrel 71 may be provided within the take-off tube 3 for the finished product in order to center the loops as they are formed and prevent distortion of the fabric during loop 30 formation through irregularities in the operation of the take-up mechanism. Such mandrel may be in the form of a tapered conical member supported within the opposite supporting tube 2 of the apparatus. Such mandrel, however, is not 35 essential to the successful operation of the apparatus and may be entirely dispensed with.

The apparatus just described have been disclosed as a horizontally arranged machine, but obviously the machine could be arranged vertically should it be more convenient for any reason 40 to have the mechanism operating in that position, and the description of the machine as being positioned horizontally is not to be taken as a limitation against its construction and use in any desired position found most convenient, as 45 the term horizontal is merely used as descriptive word for convenience of definition and not as expressing any essential position of the apparatus to be fully operative.

50 In place of fixed loop forming members reciprocating past the knitting throat, it is to be understood I may use a plurality of pivoted loop-forming elements, the ends of which are adapted to oscillate across the knitting throat. These 55 may oscillate simultaneously in one direction or alternately in opposite directions. The yarn feeds may rotate past the loop forming members, or the loop forming members may rotate past the yarn feeds as in the apparatus shown.

60 If plain purl knitted fabric is to be produced a single sleeve and set of yarns on each side of the knitting throat will suffice. If pile fabric or Milanese fabric is to be made one or more sleeves and sets of yarns must be added to one or both 65 sides, but a heavy filler yarn 12c to provide for reinforced fabric or uncut or cut pile fabric may be supplied with each tensioning yarn 12 through the same tube of a set of feeder tubes, as is shown in Figure 15.

70 The yarn feeds may be telescopically engaged and arranged so as to permit relative rotation so as to have the loops formed from any desired yarns moved into the path of the loop forming members.

75 Thus, various types of fabric may be formed

with such apparatus. Where one set of yarns is provided on each side of the knitting throat, plain purl fabric will be produced. If four sets of yarn feeders are employed, two on each side of the loop forming bars, and are revolved in opposite directions, a fabric on the order of a Milanese purl knitted fabric may be formed, and if the 80 yarns on one yarn table comprise binder yarns and the yarns on another yarn table comprise filler yarns, such as mohair or the like, a pile fabric may be formed in which the binder yarns serve to hold the fabric as a backing cloth, the tension being varied to permit the loops to be drawn tight on the binder yarns.

As heretofore stated, a single set of yarns may be provided on one side of the apparatus and a double set on the opposite end of the apparatus, which will thus permit a series of pile or plating loops to be formed on one side of the fabric, the remaining loops forming the backing for such 90 fabric. The fabric formed on the apparatus just described may be of a loose type or with the loops closely drawn.

Other forms may be employed embodying the features of my invention instead of the one here 100 explained, change being made in the form or construction, provided the fabric be produced, or the elements stated by any of the following claims or the equivalent of such stated elements be employed, whether produced by my preferred method or mechanism, or by others embodying structure, steps, or mechanism, equivalent to those 105 stated in the following claims.

I therefore particularly point out and distinctly 110 claim as my invention:

1. An apparatus of the character described, having in combination a plurality of loop-forming members disposed in spaced relation about the margin of a fabric receiving aperture, a plurality of yarn feeding elements disposed adjacent 115 said loop-forming elements and comprising at least two yarn feeding elements for each loop-forming element, means for moving said yarn feeding elements and loop-forming elements relatively to each other to feed yarn to said loop-forming elements, and means for moving said loop-forming elements and yarn feeding elements relative to each other to draw loops from one series of yarns and to cast loops from another series of yarns.

2. An apparatus of the character described, having in combination a plurality of loop-forming members disposed in spaced relation about the margin of a fabric receiving aperture, a plurality of yarn feeding elements disposed adjacent 120 said loop-forming elements and comprising at least two yarn feeding elements for each loop-forming element, means for moving said yarn feeding elements and loop-forming elements relatively to each other to feed yarn to said loop-forming elements, and means for moving said loop-forming elements and yarn feeding elements relative to each other to draw loops from one series of yarns and to cast loops from another series of yarns and to draw the cast off loops to any 125 desired size.

3. An apparatus of the character described, having in combination a plurality of loop-forming members disposed in spaced relation about the margin of a fabric receiving aperture, a plurality of yarn feeding elements disposed adjacent 130 said loop-forming elements and comprising at least two yarn feeding elements for each loop-forming element, means for moving said yarn feeding elements and loop-forming elements relatively to each other to feed yarn to said loop-forming elements, and means for moving said loop-forming elements and yarn feeding elements relative to each other to draw loops from one series of yarns and to draw the cast off loops to any 135 desired size.

4. An apparatus of the character described, having in combination a plurality of loop-forming members disposed in spaced relation about the margin of a fabric receiving aperture, a plurality of yarn feeding elements disposed adjacent 140 said loop-forming elements and comprising at least two yarn feeding elements for each loop-forming element, means for moving said yarn feeding elements and loop-forming elements rel-

- atively to each other to feed yarn to said loop-forming elements, means for moving said loop-forming elements and yarn feeding elements relative to each other to draw loops from one series of yarns, and means to draw the cast off loops to any desired size.
4. An apparatus of the character described, having in combination a plurality of loop-forming members disposed in spaced relation about the margin of a fabric receiving aperture, a plurality of yarn feeding elements disposed adjacent said loop-forming elements and comprising at least two yarn feeding elements for each loop-forming element, means for moving said yarn feeding elements and loop-forming elements relatively to each other to feed yarn from one alternately positioned series of yarn feeding elements to said loop-forming elements, and means for moving said loop-forming elements and yarn feeding elements relative to each other to draw loops from the series of yarns so supplied by said yarn feeding elements and to cast off loops from the other series of yarns from said series of loop-forming elements.
5. An apparatus of the character described, having in combination a plurality of loop-forming members disposed in spaced relation about the margin of a fabric receiving aperture, a plurality of yarn feeding elements disposed adjacent said loop-forming elements and comprising at least two yarn feeding elements for each loop-forming element, means for moving said yarn feeding elements and loop-forming elements relatively to each other to feed yarn from one alternately positioned series of yarn feeding elements to said loop-forming elements, and means for moving said loop-forming elements and yarn feeding elements relative to each other to draw loops from the series of yarn so supplied by said yarn feeding elements and to cast off loops from the other series of yarns from said series of loop-forming elements and to draw the cast off loops to any desired size.
6. An apparatus of the character described, having in combination a plurality of loop-forming members disposed in spaced relation about the margin of a fabric receiving aperture, a plurality of yarn feeding elements disposed adjacent said loop-forming elements and comprising at least two yarn feeding elements for each loop-forming element, means for moving said yarn feeding elements and loop-forming elements relatively to each other to feed yarn from one alternately positioned series of yarn feeding elements to said loop-forming elements, and means for moving said loop-forming elements and yarn feeding elements relative to each other to draw loops from the series of yarns so supplied by said yarn feeding elements and to cast off loops from the other series of yarns from said series of loop-forming elements, and means to draw the cast off loops to any desired size.
7. An apparatus of the character described, having in combination a plurality of loop-forming members disposed in spaced relation about the margin of a fabric receiving aperture, a plurality of yarn feeding elements disposed adjacent said loop-forming elements and comprising at least two yarn feeding elements for each loop-forming element, means for moving said yarn feeding elements and loop forming elements relatively to each other to feed yarn to one side of said loop-forming elements, and means for moving said yarn feeding elements and loop-forming ele-
- ments relatively to each other so as to draw loops from the series of yarns so supplied to said loop-forming elements and to cast off loops from a previously supplied series of yarn fed to the other side of said loop-forming elements and to tension such cast off loops.
8. An apparatus of the character described, having in combination a plurality of loop-forming members disposed in spaced relation about the margin of a fabric receiving aperture, a plurality of yarn feeding elements disposed adjacent said loop-forming elements and comprising at least two yarn feeding elements for each loop-forming element, means for moving said yarn feeding elements and loop-forming elements relatively to each other to feed yarn to one side of said loop-forming elements, means for moving said yarn feeding elements and loop-forming elements relatively to each other so as to draw loops from the series of yarns so supplied to said loop-forming elements and to cast off loops from a previously supplied series of yarns fed to the other side of said loop-forming elements, and means to tension such cast off loops.
9. An apparatus of the character described, having in combination a plurality of loop-forming members disposed in spaced relation about the margin of a fabric receiving aperture, a plurality of yarn feeding elements disposed adjacent said loop-forming elements and comprising at least two yarn feeding elements for each loop-forming element, means for moving said yarn feeding elements and loop-forming elements relatively to each other to feed yarn to said loop-forming elements, means for moving said loop-forming elements and yarn feeding elements relative to each other to draw loops from one series of yarns and to cast loops from another series of yarns, and means to grip the individual yarns of the cast off series of yarns and move the same relatively to the fabric margin to draw the cast off loops to any desired size.
10. An apparatus of the character described, having in combination a plurality of loop-forming members disposed in spaced relation about the margin of a fabric receiving aperture, a plurality of yarn feeding elements disposed adjacent said loop-forming elements and comprising at least two yarn feeding elements for each loop-forming element, means for moving said yarn feeding elements and loop-forming elements relatively to each other to feed yarn to said loop-forming elements, means for moving said loop-forming elements and yarn feeding elements relative to each other to draw loops from one series of yarns and to cast loops from another series of yarns, and means to grip the individual yarns of the cast off series of yarns and move the same relatively to the fabric margin to draw the cast off loops to any desired size and to maintain the tension thereon while said loop-forming members are drawing a new series of loops.
11. An apparatus of the character described, having in combination a fabric receiving member disposed centrally of said apparatus and providing an opening through which finished fabric may be received, a member disposed adjacent the fabric receiving end of said member and in spaced relation thereto to define a knitting throat, a series of loop-forming members disposed in spaced relation about said knitting throat, a series of yarn feeding members disposed in spaced relation about said knitting throat, means causing relative movement between said yarn feeding elements and said loop-

- forming elements radially about said knitting throat, and means for producing relative motion between said loop-forming members and said knitting throat in a direction substantially axially of said fabric receiving member to draw and cast loops in the process of fabric manufacture. 5 80
12. A method of knitting which comprises the steps of forming loops upon a plurality of knitting elements from one series of binder yarns, 10 and casting off from said knitting elements the loops from a second series of binder yarns, and forming filler loops from a third series of yarns over certain of said binder yarns, and drawing the yarns of the second series of binder yarns to draw said cast-off loops into tight locking engagement with said filler loops. 15 85
13. A method of fabric manufacture which comprises the steps of supplying from one side to knitting instrumentalities, upon each of which 20 is engaged a previously formed loop of yarns, new yarns from the other side from one series and casting from said instrumentalities yarns from a companion series, and drawing said cast-off 25 yarns to produce loops on a previously formed series of yarns, said loops being drawn to any desired size. 90
14. A pile fabric having a knitted backing fabric, the loops of said pile fabric being looped around the respective yarns of the knitted backing fabric intermediate the knitted loops thereof. 95
15. A pile fabric having a purl knitted backing fabric, the loops of said pile fabric being looped around the looped portions of the respective 30 yarns of the knitted backing fabric and held in tightly locked relation thereto through the seating of loops of alternate yarns of said fabric upon loops formed from a companion series of 35 yarns. 100
16. An apparatus of the character described, having in combination a fabric receiving member disposed centrally of said apparatus and providing an opening through which finished fabric 40 may be received, a member disposed adjacent the fabric receiving end of said member and in spaced relation thereto to define a knitting throat, a series of loop-forming members disposed in spaced relation about said knitting 45 throat, a series of yarn feeding members disposed in spaced relation about said knitting throat, certain of said yarn feeding elements being adapted to supply binder yarns to said loop-forming elements and certain of said yarn feeding 50 elements being adapted to supply filler yarns to said loop-forming elements, means causing relative movement between said yarn feeding elements and said loop-forming elements radially about said knitting throat, and means for producing relative motion between said loop-forming members and said knitting throat in a direction substantially axially of said fabric receiving member to draw and cast loops in the process of fabric manufacture. 55 110
17. An apparatus of the character described, having in combination a fabric receiving member disposed centrally of said apparatus and providing an opening through which finished fabric 60 may be received, a member disposed adjacent the fabric receiving end of said member and in spaced relation thereto to define a knitting throat, a series of loop-forming members disposed in spaced relation about said knitting 65 throat, certain of said yarn feeding elements being adapted to supply binder yarns to said loop-forming elements and certain of said yarn feeding elements being adapted to supply filler yarns to said loop-forming elements, means causing relative movement between said yarn feeding elements and said loop-forming elements radially about said knitting throat, and means for producing relative motion between said loop-forming members and said knitting throat in a direction substantially axially of said fabric receiving member to draw and cast loops in the process of fabric manufacture. 70 115
18. An apparatus of the character described, having in combination a fabric receiving member disposed centrally of said apparatus and providing an opening through which finished fabric 75 may be received, a member disposed adjacent the fabric receiving end of said member and in spaced relation thereto to define a knitting throat, a series of loop-forming members disposed in spaced relation about said knitting throat, a series of yarn feeding members disposed in spaced relation about said knitting throat, means for causing relative motion radially of said fabric receiving member and the binder yarn feeding elements, means for causing relative motion radially of said fabric receiving members of the filler yarn feeding elements, means causing relative movement between said yarn feeding elements and said loop-forming elements radially about said knitting throat, and means for producing relative motion between said loop-forming members and said knitting throat in a direction substantially axially of said fabric receiving member to draw and cast loops from said binder in the process of fabric manufacture. 80 120
19. An apparatus of the character described, having in combination a fabric receiving member disposed centrally of said apparatus and providing an opening through which finished fabric 85 may be received, a member disposed adjacent the fabric receiving end of said member and in spaced relation thereto to define a knitting throat, a series of loop-forming members disposed in spaced relation about said knitting 90 throat, a series of yarn feeding members disposed in spaced relation about said knitting throat, means for causing relative motion radially of said fabric receiving member and the binder yarn feeding elements, means for causing relative motion radially of said fabric receiving members of the filler yarn feeding elements, means for drawing filler yarns over portions of binder yarns and out of the path of the loop-forming elements engaging said binder yarns to produce filler yarn loops when said binder yarns 95 are engaged by their respective loop-forming members, means causing relative movement between said yarn feeding elements and said loop-forming elements radially about said knitting throat, and means for producing relative motion between said loop-forming members and said knitting throat in a direction substantially axially of said fabric receiving member to draw and cast loops from said binder in the process of fabric manufacture. 100 125
20. An apparatus of the character described, having in combination a fabric receiving member disposed centrally of said apparatus and providing an opening through which finished fabric 105 may be received, a member disposed adjacent the fabric receiving end of said member and in spaced relation thereto to define a knitting throat, a series of loop-forming members disposed in spaced relation about said knitting 110 throat, a series of yarn feeding members disposed in spaced relation about said knitting throat, means for causing relative motion radially of said fabric receiving member and the binder yarn feeding elements, means for causing relative motion radially of said fabric receiving members of the filler yarn feeding elements, means for drawing filler yarns over portions of binder yarns and out of the path of the loop-forming elements engaging said binder yarns to produce filler yarn loops when said binder yarns are engaged by their respective loop-forming members, means causing relative movement between said yarn feeding elements and said loop-forming elements radially about said knitting throat, and means for producing relative motion between said loop-forming members and said knitting throat in a direction substantially axially of said fabric receiving member to draw and cast loops from said binder in the process of fabric manufacture. 115 130
21. An apparatus of the character described, having in combination a fabric receiving member disposed centrally of said apparatus and providing an opening through which finished fabric 120 may be received, a member disposed adjacent the fabric receiving end of said member and in spaced relation thereto to define a knitting throat, a series of loop-forming members disposed in spaced relation about said knitting 125 throat, a series of yarn feeding members disposed in spaced relation about said knitting throat, means for causing relative motion radially of said fabric receiving member and the binder yarn feeding elements, means for causing relative motion radially of said fabric receiving members of the filler yarn feeding elements, means for drawing filler yarns over portions of binder yarns and out of the path of the loop-forming elements engaging said binder yarns to produce filler yarn loops when said binder yarns are engaged by their respective loop-forming members, means causing relative movement between said yarn feeding elements and said loop-forming elements radially about said knitting throat, and means for producing relative motion between said loop-forming members and said knitting throat in a direction substantially axially of said fabric receiving member to draw and cast loops from said binder in the process of fabric manufacture. 130 135
22. An apparatus of the character described, having in combination a fabric receiving member disposed centrally of said apparatus and providing an opening through which finished fabric 135 may be received, a member disposed adjacent the fabric receiving end of said member and in spaced relation thereto to define a knitting throat, a series of loop-forming members disposed in spaced relation about said knitting 140 throat, a series of yarn feeding members disposed in spaced relation about said knitting throat, means for causing relative motion radially of said fabric receiving member and the binder yarn feeding elements, means for causing relative motion radially of said fabric receiving members of the filler yarn feeding elements, means for drawing filler yarns over portions of binder yarns and out of the path of the loop-forming elements engaging said binder yarns to produce filler yarn loops when said binder yarns are engaged by their respective loop-forming members, means causing relative movement between said yarn feeding elements and said loop-forming elements radially about said knitting throat, and means for producing relative motion between said loop-forming members and said knitting throat in a direction substantially axially of said fabric receiving member to draw and cast loops from said binder in the process of fabric manufacture. 140 145
